UNITED STATES PATENT OFFICE.

HERMAN LEINEWEBER, OF CHICAGO, ILLINOIS.

BOLT-GUN.

SPECIFICATION forming part of Letters Patent No. 527,369, dated October 9, 1894.

Application filed August 17, 1893. Serial No. 483,408. (No model.)

To all whom it may concern:

Be it known that I, HERMAN LEINEWEBER, a citizen of the United States, residing at Chicago, in the county of Cook and State of Illinois, have invented a new and useful Improvement in Firearms, of which the following is a specification.

This invention relates to an improvement in the variety of small arms, in which a spring-controlled firing-pin is confined in a breech block adapted to be rocked back and forth by hand on its longitudinal axis for locking and unlocking it and setting the spring of the firing-pin and to be reciprocated lengthwise to open the breech for loading and advancing the cartridge into the barrel.

The object of this invention is to provide a gun in the class referred to, which shall involve the utmost simplicity in its construction to the exclusion of springs, except one for the firing-pin and one for the trigger and which shall, in consequence, be the least liable to impairment of the mechanism or to its becoming inoperative by use.

My invention consists in details of construction and combination of parts whereby my aforesaid object is attained.

In the accompanying drawings—Figure 1 is a broken view in longitudinal section of my improved gun, showing parts in elevation and the breech-block withdrawn to its full limit. Fig. 2 is a plan partly in section taken at the line 2—2 on Fig. 1 and viewed in the direction of the arrows. Fig. 3 is a view like that presented in Fig. 1, but showing more of the details of construction in sectional elevation, and the breech-block in the receiver. Fig. 4 is a broken sectional plan view of the rear portion of the receiver and showing the guide-slot extending behind it. Figs. 5, 6 and 7 are sectional views taken, respectively, at the line 5 on Fig. 3, and the lines 6 and 7 on Fig. 1, and viewed as indicated by arrows. Fig. 8 is a broken view in side elevation showing the details of the cam-mechanism on the rear ends of the breech-block and firing-pin.

A denotes the stock and B is the barrel, neither of which involves any feature of novelty.

C is the receiver, in generally tubular form, having an elongated opening C' on its right side through which to insert a cartridge C²,

in loading, and through which the shell of the discharged cartridge is thrown out, as hereinafter described. The barrel is screwed, at 55 its rear end, into the forward end of the receiver, thereby presenting at the junction, in the receiver, an annular shoulder r, the obstructing tendency of which to the cartridge, in sliding the latter into the barrel by 60 the forward movement of the reciprocating breech-block D, it is one of the primary objects to overcome, and which is overcome by providing in the base of the receiver, adjacent to the opening C', a depression C³, tapering toward its forward end and deepening toward its rear, flaring end, to approximate the shape of the cartridge which seats in it on being inserted into the breech through its said opening. The shape of the depression C³ is 70 thus such, as to compensate for the taper of the cartridge, which, if its seat in the receiver were even throughout, would point against the shoulder r and be forced against the latter in shoving the cartridge into place by means 75 of the reciprocating breech-block, the force of contact with the obstruction tending to disarrange and even loosen the connection between the bullet and shell of the cartridge. The depression C³ compensates for the taper 80 of the cartridge in the sense that it deepens the seating toward the flaring end thereof sufficiently to cause the opposite end to point in the plane, or more toward the center, of the bore of the barrel, whereby, when the 85 cartridge is shoved into the latter, it will clear the obstruction. The receiver C is internally enlarged, circumferentially, from near the rear end of the opening C' for a sufficient distance backward to afford a rectangular 90 circumferential groove q from which rectangular side-grooves p extend longitudinally of the receiver backward to its rear end. A rear extension E of the lower section of the receiver C contains in its base a central longitudinal rectangular groove o, and is provided in its right side, at the rear end of the receiver, with a recess o' to receive the lever G of the breech-block D, as hereinafter described. In the side of the receiver opposite that provided with the opening C', is a spring-dog C⁴ (Figs. 2 and 6) extending at its rear end t through the wall of the receiver into the latter and having, at its opposite

end, a button t' by which to compress it against the spring t^2 to withdraw the stop.

The breech-block D is in the form of a cylindrical tube containing the spring-controlled firing-pin D' and adapted to fit inside and be reciprocated lengthwise, and turned back and forth on its longitudinal axis in the receiver, being held, normally, from withdrawal by the stop t of the spring-dog C⁴ extending 5 into a longitudinal groove n in a side of the breech-block and which has a right-angular termination n' at its rear end to permit turning of the breech-block on its longitudinal axis to lock it. The locking is effected 10 through the medium of the ears m, m , on opposite sides of the breech-block behind the plane of the groove-termination n' and which enter the guide-grooves p in the sides of the breech when the breech-block is being inserted 15 therein, but which are in the circumferential groove q when the breech-block is fully inserted, whereby it may be turned, through the medium of the usual lever G, on its longitudinal axis to bring the ears m respectively 20 in the upper and lower portions of the groove q , wherein they are out of coincidence with the guide-grooves p and confined in the circumferential groove to lock the breech-block in the receiver. When the 25 breech-block is thus turned toward the right, after being inserted in the receiver, to lock it therein, the shank of the lever G enters the notch or recess o' .

The firing-pin D' is of the usual general 30 form, being adapted to work, at its pointed end, through a central opening x in the head of the breech-block. The spring D², which is coiled around the firing-pin to control it, is confined between the rear end of the 35 breech-block and the head x' of the firing-pin, the last turn of the spring adjacent to the head x' , however, being extended at its end v' into a longitudinal groove v in the wall of the breech-block, for a purpose hereinafter described.

Near its rear end, the firing-pin is reduced and flattened on opposite sides, as shown at a in Figs. 3 and 5, and on this reduced portion fits a sleeve F, held in place by a nut b 40 engaging the thread b' and forming the rear termination of the firing-pin. The sleeve F carries a rigid cam l to engage with an opposing cam-surface l' formed on the rear end of the breech-block, which terminates at its 45 outer extremity in a shoulder l''. A lug k projects from the bottom of the sleeve F to enter the groove O in the base of the extension E.

On the rear end of the breech-block, adjacent to the lever G, is a well-known form of pivoted safety-catch G' to lock the firing-pin against operation when set for firing and in case of being accidentally released by the trigger.

H is the trigger-mechanism, comprising the finger-portion i, pivotally connected at s with the rear end of a lever h fulcrumed between

its ends on the base of the receiver C to extend lengthwise thereof. The lever h terminates at one end in a stop-lug k' which projects upward through the breech-extension E into the groove o, thus into the path of the lug k on the rear end of the firing-pin; and at its opposite end the lever h terminates in a head h' affording a socket to confine a spiral spring g in its seat g' in the under side of the breech C. The trigger-finger i is extended backward, at its upper end, to form bearings f and f', which afford two fulcrums against the base of the part E, operating successively 75 in pulling the trigger.

The head of the tubular breech-block, which may be screwed into place, as represented, (and which has its central aperture x formed in the shape of the pointed end of the firing-pin) terminates, in line with the longitudinal groove n , in a forward projecting lip e, and directly opposite in the side of the breech-block is formed a longitudinal groove d' having fastened in it a flat spring 90 d projecting at its forward end beyond the head of the breech-block in the form of a lip e' to co-operate with the opposing lip e to engage the rim at the rear end of a cartridge and afford an extractor for the shell. Immediately adjacent to the lip e, a loosely reciprocating pin c coincident with the groove n extends through the breech-block head from a recess or chamber c' formed at the rear of said head at the end of the groove n where 100 a head c² on the inner end of the pin projects through the plane of the groove flush with the circumference of the cylindrical breech-block.

The operations of loading and firing the gun 105 are performed as follows: The breech-block being in place, having been inserted into the receiver C, and turned to the right to lock it therein (presumably after the gun has been fired) it next devolves upon the operator to 110 set the firing-pin and withdraw and throw out the shell of the spent cartridge preparatory to reloading and again firing. The first operation is to turn the breech-block, by its handle G, toward the left. As the primary 115 result of this, the cam-face l' on the end of the breech-block, by the turning of the latter, works against the opposing cam l on the firing-pin, which cannot turn owing to the lug k being confined in the groove o. Hence 120 the pin is cammed backward, compressing and thus setting the spring D², until the cam l seats against the shoulder l'', which prevents retraction of the firing-pin by its controlling-spring. Then, the ears m being in line with 125 the grooves p in the side of the receiver C, the breech-block may be withdrawn, as far as the spring-dog C⁴ will permit. The withdrawal of the breech-block, by the hold of the lips e and e' on the flange of the cartridge-shell, pulls the latter out of the barrel into the receiver C; and when the breech-block reaches the extremity of its withdrawal, the limiting lug t in the groove n is struck by the 130

head c^2 of the pin c , thereby driving the latter suddenly forward and forcing the shell from the grip of the holding-lips e and e' , and out through the side-opening C' in the receiver. 5 Then a cartridge C^2 may be inserted, through the side-opening C' , into its seat C^3 in the receiver C , and by sliding the breech-block longitudinally inward it shoves the cartridge ahead of it into the barrel B , meantime having gripped the flange between the lips e , e' . When the breech-block has thus been inserted it is turned to cause the ears m , m to lock it as described. However this turning of the breech-block, while it separates the cam-face l' from the cam l , does not release the firing-pin, since the latter is held set by the abutment of the lug k against the spring-stop k' of the trigger-mechanism. On pulling the trigger, whereby the stop k' is 10 depressed out of the path of the lug k , the firing-pin is freed, to be shot forward by the recoil of its controlling-spring, to fire the cartridge.

20 In turning the breech-block toward the left to set the firing-pin spring, the tendency of the latter would be to unwind, were it not for retaining the end v' thereof in the slot v , where-

by such unwinding tendency is not only prevented, but the tension of the spring, in setting, is exerted to tend to force the cam l in 30 the direction toward its seating-shoulder l^2 .

What I claim as new, and desire to secure by Letters Patent, is—

In a gun, the combination with the barrel, stock and suitable trigger-mechanism, of an 35 interposed receiver C in the forward end of which the rear end of the barrel is fastened, a reciprocating breech-block confined in the receiver to turn on its longitudinal axis, and provided with an internal longitudinal groove 40 v , a firing-pin D' , in the breech-block, having a controlling-spring D^2 confined upon it with one end v' thereof confined in the groove v , locking-means at the rear end of the breech-block operated by turning it in the 45 receiver, and cam-mechanism at the rear ends of the firing-pin and breech-block, cooperating, by turning the breech-block to unlock it, to set the spring of the firing-pin, substantially as described.

HERMAN LEINEWEBER.
